LIPA POLINKOWSKY, OF BRUSSELS, BELGIUM, ASSIGNOR TO WESTERN ELECTRIC COMPANY, OF NEW YORK, N. Y., A CORPORATION OF ILLINOIS.

MACHINE TELEPHONE SWITCHING SYSTEM.

1,160,447.

Specification of Letters Patent. Patented Nov. 16, 1915.

Application filed March 5, 1914. Serial No. 822,589.

To all whom it may concern:

Be it known that I, LIPA POLINKOWSKY, a subject of the Russian Emperor, residing at 19 Rue Brialmont, Brussels, Belgium, 5 have invented certain new and useful Improvements in Machine Telephone Switching Systems, of which the following is a full, clear, concise, and exact description.

This invention relates to machine switch- 10 ing telephone exchange systems and more particularly to improvements in systems in which an automatically operating switch searches for and seizes an idle one of a plurality of circuits or sets of circuits.

15 One of the features of the invention provides such an arrangement of circuits and apparatus that the switch which operates to search for and seize an idle circuit or sets of circuits from a plurality of circuits or sets of 20 circuits, may be of simple and efficient design operating at high speed and producing positive contact between the circuit to be extended and the circuit or circuits seized.

A more specific feature of the invention 25 relates to the arrangement of circuits and apparatus whereby an automatically operating power driven switch which may be of the type known to the art as a sequence switch may be used to extend a single circuit or set of circuits to an idle one of a group of circuits or sets of circuits to which such switch has access, such arrangement of circuits and apparatus involving particularly the test circuit by which such sequence 30 switch is controlled and the relation of such test circuit, and particularly of the contacts of such sequence switch forming a part thereof, with the circuits under test and the contacts of such sequence switch adapted to 35 form a part of a selected circuit when seized.

Other novel features will sufficiently appear from a description of the embodiment of the invention shown in the drawings, in which:—

45 Figure 1 shows the invention as embodied in a machine switching telephone system in which a connecting circuit is to have associated therewith one of a plurality of registering and controlling equipments for the 50 purpose of extending the connection desired over such connecting circuit. Fig. 2 is a graphic representation of the time relation of the closure of certain of the sequence switch contacts shown in Fig. 1.

55 In the drawings 600 represents a sequence

switch associated with the connecting circuit referred to. All of the sequence switch contacts indicated above the upper dotted line of Fig. 1 are either directly controlled by the sequence switch 600, such as sequence 60 switch springs 601, 604, 607, 613, 616, and 617, or are associated with some other sequence switch in turn associated with the same connecting circuit, and may be indirectly controlled by such sequence switch 65 600, as, for example, the sequence switch springs 206 and 210. On the other hand the sequence switch springs 401, 406 and 405 shown below the lower dotted line of Fig. 1 form a part of a sequence switch 400 associated with one of the registering and controlling equipments to which the connecting 70 circuits referred to has access.

Between the dotted lines of Fig. 1 is shown a sequence switch 700 which is adapted to search for and seize an idle registering and controlling equipment. All of the sequence switch contacts indicated between the two dotted lines are associated with such sequence switch 700. The positions of the 80 sequence switch springs of this sequence switch are closed as shown in the usual manner by the numerals adjacent to such springs; for example, the spring 704 is closed in position 2 to its bottom contact; the 85 same spring is closed in position 5 to its top contact, such spring being closed to either of its contacts only in the positions noted. On the other hand the springs 701 and 703 are open only in the positions noted adjacent 90 thereto, this being indicated by having the numerals on the opposite side of the respective springs from the contacts with which they coöperate.

It is the function of the sequence switch 95 700 in the embodiment of the invention shown to connect the leads 11, 12, 13, 14, leading from a connecting circuit, to leads such as 21, 22, 23, 24 of an idle registering and controlling equipment. The particular 100 leads 21, 22, 23, 24 shown are those associated with that equipment to which the leads 11, 12, 13, 14 will be connected when the sequence switch 700 stands in its second position. It will be understood of course that 105 there may be another equipment for each of the other positions of the sequence switch to which the leads 11, 12, 13, 14 will be connected when such sequence switch 700 stands in such other positions. In the embodiment 110 110

shown the sequence switch 700 is indicated as being provided with six positions, and the leads of five other registering and controlling equipments, than the one to which the leads 21, 22, 23, 24 are individual, are indicated, one set of such leads being connected to by such sequence switch in its first position; another in its third position; another in its fourth position; another in its fifth position; and still another in its sixth position.

The lead 15 connected to the springs 704, 705, 706 forms part of the test circuit of the sequence switch 700. Correspondingly the lead 25 is the test conductor individual to the registering and controlling equipment indicated to which the sequence switch 700 will connect the leads from the connecting circuit in its second position.

The invention will be further best understood from a description of the operation of the embodiment thereof shown in the drawings. It will be assumed that a call exists upon the connecting circuit with which the circuits and apparatus shown above the upper dotted line in Fig. 1 of the drawings are associated, and that as the result of the receipt of this call the sequence switch 600 has been brought into its second position, as has also the sequence switch controlling the springs 206 and 210. In the second position of the sequence switch 600 a circuit will be established over the back contact of the relay 240, spring 613, and spring 702 for the sequence switch 700. Under the control of the spring 701 the sequence switch 700 can only come to rest in one of its definite positions as is usual in switches of this type. However, at the time of the establishment of the circuit just traced no circuit could exist for the relays 240 and 235 even though the spring 604 is at that time closed on account of the fact that the spring 703 is open in each definite or stopping position of the sequence switch 700. The sequence switch 700 will therefore start in motion, and in this movement will test for an idle registering and controlling equipment of the plurality of such equipments to which it has access. The idle condition of one of such equipments will be indicated by full battery potential existent upon the contact to which the lead 25 of such equipment is connected, such potential being applied to such lead by the closure of the spring 405, which spring is only closed when the registering and controlling equipment of which it forms a part is in its normal or idle position as indicated by the numeral 1 placed adjacent such spring 405 upon the drawings. It will be observed that when the registering and controlling equipment indicated below the lower dotted line on Fig. 1 has been seized, the relay 426 is energized, and drives the sequence switch

400 of such equipment out of its normal position, thereby opening the direct circuit to battery, but substituting before such circuit is opened a circuit through the front contact of the relay 426, spring 406 and resistance 451, which will be sufficient to maintain the relays in the test circuit which has seized such equipment, energized, but will not place sufficient potential upon the contacts to which the lead 25 is multiplied in the sequence switches 700 of the various connecting circuits having access to such equipment to allow the operation of the test relays thereof.

At this point it should be observed that the leads of each of the registering and controlling equipments to which the sequence switch 700 has access, may be multiplied to sequence switches corresponding to the sequence switch 700 of a whole group of connecting circuits, and one or more of such registering and controlling equipments may be busy or idle at any given time, any one of such group of registering and controlling equipments equally well serving for association with any one of a larger group of connecting circuits with each of which connecting circuits there is associated a sequence switch such as the sequence switch 700.

As has been above described, the sequence switch 700 shown on the drawings has been started in motion when the sequence switch 600 came into its second position. As the sequence switch 700 leaves the position in which it now stands, assuming, for example, that it stands in its No. 1 position, the spring 701 thereof will be closed to insure the movement of such sequence switch completely into its second position. A definite period after such sequence switch has started to move from its first position, the spring 706 top will be opened. It is only after the opening of the spring 706 top as the sequence switch 700 is moving from its first position that the spring 703 will be closed and such spring 703 furthermore will be again opened either before, or simultaneously with, the opening of the spring 701 as the sequence switch 700 is coming into its second position. Furthermore as the sequence switch 700 is coming into its second position the spring 704 bottom will be closed for a definite period before the opening of the spring 703. It is during this period, in which the spring 703 and the spring 704 bottom are both closed, that the test to determine the busy or idle condition of the register controlling equipment to which the sequence switch 700 will be connected in its second position, is made. If at this time this equipment is idle, full battery potential will be found upon the contact with which the spring 704 makes circuit on its lower side. Such being the case, the relay 235 will receive sufficient cur-

rent through its right-hand high resistance winding to cause the energization of such relay, and such relay, together with the relay 240 will be energized. The energization 5 of the relay 235 establishes a low resistance path through its left winding and its own armature as well as through the relay 237, which so reduces the potential upon the lead 25 that no other sequence switch 700 testing 10 for an idle registering and controlling equipment will be able to have its relays 235 and 240 energized at this time. The energization of the relay 240 opens the power circuit of the sequence switch 700 and substitutes a direct ground connection through its armature and front contact for the ground connection of the test circuit which at this 15 time exists through the spring 703. The springs 701 and 703 in the further movement 20 of the sequence switch 700 now open as such sequence switch comes into its second position, and the sequence switch 700 will stop in such position.

The energization of the relay 237 by the 25 closure of the contact of the relay 235 closes a circuit over its front contact and the spring 607 to drive the sequence switch 600 out of its second position. Such sequence switch coming into and stopping in its third 30 position opens the springs 604, 607 and 613, and closes the springs 616 and 617, and also indirectly closes the springs 206 and 210. At the same time that the relay 235 was energized, the relay 426 was energized, and 35 drove the sequence switch 400 out of its first position, opening the spring 405 and closing the spring 406. This so reduces the potential 40 upon the contacts in the sequence switches 700 to which the lead 25 of the seized equipment is multiplied, that the leads to this equipment may not be connected to or seized by any other connecting circuit even though the spring 604 is now open. The closure, however, of the springs 206, 45 210, 616 and 617 connects the four leads 11-21, 12-22, 13-23, 14-24 through from the connecting circuit to the seized registering and controlling equipment.

In the case assumed, however, if the equipment 50 to which the leads of the sequence switch 700 will be connected in its second position was busy as the sequence switch 700 came into its second position, the relays 235 and 240 would not have been energized, 55 and when the spring 701 was opened as the sequence switch 700 came into the second position, power would still be supplied to such sequence switch over the back contact of the relay 240 and the spring 613, and the 60 sequence switch 700 would continue to move through its second position and into its third position. On leaving its second position the spring 701 would again be closed. In this movement after the spring 704 bottom 65 is opened, the spring 703 would be

closed, and for a definite period before the opening of the springs 701 and 703 the spring 705 top would be closed. In the period after the closure of the spring 705 top, and before the opening of the spring 70 703 a test would be made of the busy or idle condition of the registering and controlling equipment to which the leads of the sequence switch 700 would be closed in its third position precisely as was the condition of the 75 registering and controlling equipment to which the sequence switch 400 shown is individual was tested as the sequence switch 700 was coming into its second position. If at this time the third registering and controlling equipment (that is, the one to which the sequence switch 700 makes connection in its third position) is idle, the relays 235 and 240 will be energized as has already been described, causing the sequence switch 700 80 to stop in its third position, and extend connection to such third equipment, the sequence switch 600 being at the same time moved into its third position to complete the circuit of the leads extending from the connecting circuit to such third equipment. On the other 85 hand if the third equipment was busy at this time, the sequence switch 700 would be continued in motion through its third position by the maintained closure of the circuit including the back contact of the relay 240 and the spring 613, and it would continue in motion to its fourth position in such movement testing in a corresponding manner the 90 busy or idle condition of the fourth equipment to which such sequence switch 700 has access.

The utility of the spring 703 and the particular timed relation between the closure of such spring and the closure of the springs 701, 704, 705 and 706 will be apparent if it is assumed that as the sequence switch 700, having tested the second equipment as it was coming into the second position, is moving out of such second position, and the spring 701 is again closed, such second equipment 105 should become idle before the spring 704 bottom is opened. In this case if the connection to ground from the relay 240 were direct instead of through the spring 703 110 which is open at this time, the relays 235, 240 and 237 would be energized, but the sequence switch 700 would continue in motion due to the closure of the spring 701 until it came into its third position. At this time 115 it might be possible that the relays 235, 240 and 237 would be maintained energized over the circuit including the lead 25 of the third equipment even though such equipment is busy, and confusion would obviously result 120 due to the connection of two connecting circuits to the same registering and controlling equipment. A more probable difficulty, however, would arise from the fact that the 125 relay 237, having once been energized, the 130

sequence switch 600 has left its second position and come into its third position as a result of which the springs 206, 210, 216, and 217 are closed. If the third registering and controlling equipment is busy, the closure of these springs while the sequence switch 700 is passing through its third position will establish circuits to such third equipment which would detrimentally affect the operation of such equipment. Correspondingly if the fourth equipment is also busy as the sequence switch 700 passed through its fourth position, the closure of the springs 206, 210, 216, and 217 would also detrimentally affect the operation of such fourth registering and controlling equipment. To prevent this interference with equipments already in use, the spring 703 is arranged so that it is not closed until after the spring 704, 705, 706 top or bottom, is opened as the sequence switch 700 leaves the position in which such spring is respectively closed. This relation between the several springs is plainly set forth in Fig. 2 of the drawings. It will be observed from this figure that spring 706 top is closed in position 1 (the vertical lines of this figure representing the stopping positions of the sequence switch 700 as indicated by the numeral at the top respectively of such lines). In position 1, furthermore, the spring 701 and the spring 703 are both open.

As the sequence switch 700 starts from its first position, the spring 701 is closed to insure its complete movement into its second position. Shortly before the sequence switch 700 comes to a position midway between its first and second position, the spring 706 top is opened. After the spring 706 is opened, the spring 703 is closed. Shortly after the sequence switch 700 has passed the point midway between its first and second positions, the spring 704 bottom is closed. At this time the spring 701, 703 and 704 bottom are all closed, and the test of the second equipment takes place. After a definite further movement of the sequence switch 700, the spring 703 is again opened, and shortly thereafter, or simultaneously therewith, the spring 701 is opened, the opening of the spring 701 taking place a sufficient period before the sequence switch 700 comes into its second position to insure that such sequence switch does not run through its second position of its own momentum even though the power circuit thereof is at that time opened. In the second position of the sequence switch, both the springs 701 and 703 are opened but the spring 704 is closed. Correspondingly in the movement of the sequence switch 700 from its second to its third position the spring 704 bottom is closed until shortly before the sequence switch comes to a point midway between its second and third positions. On the other hand, shortly after the sequence switch left

its second position, the spring 701 was closed to insure the movement of such sequence switch fully into its third position. After the spring 704 bottom was opened in this movement, the spring 703 is again closed, and furthermore after the sequence switch 700 has passed the point midway between its second and third positions, the spring 705 top is closed. As the springs 701 and 703 are not again opened in this movement until shortly before the sequence switch comes into its third position, there is a definite period during which the springs 705 top and 703 are both closed. This period is sufficient for the testing of the third equipment to which the sequence switch 700 has access.

It will be observed, therefore, from Fig. 2, that as the spring 703 is never closed in the movement of the sequence switch 700 from one position to the next until the point midway between such two positions has been reached, no false test can be made due to the idle condition of the equipment individual to the position of the sequence switch 700 from which such sequence switch is moving. Furthermore as the spring 703 is opened in the movement of the sequence switch 700 from one position to the next not later than the spring 701 is opened, it is impossible for the relays 235 and 240 to be energized after the spring 701 has been opened due to the equipment individual to the position in which the sequence switch 700 is now moving becoming idle so late in such movement that the sequence switch 700 will not be able to stop in the position individual to such equipment: that is to say, if the spring 703 were not opened before, or simultaneously with, the spring 701, it might be that the relays 235 and 240 (which latter relay maintains the power circuit for the sequence switch 700 after the spring 701 is opened) would be energized to open the power circuit for such sequence switch 700 so late that such sequence switch would pass through the position into which it is coming of its own momentum, and would again close the spring 701, which closure would cause the sequence switch 700 to continue on into its next position in spite of the fact that the relays 235, 240 and 247 having been once energized the sequence switch 600 has been driven from its second position.

As has been above described, the movement of the sequence switch 600 from its second position before an idle equipment has been properly seized would cause disturbance in any busy equipments the contacts of which may be closed in the further movement of the sequence switch 700 seeking an idle equipment.

It will be apparent, therefore, that in the embodiment of the invention shown in Fig. 1 no false test can take place, and no interference with busy equipments will result

even though the sequence switch 700 in its searching operation closes its springs to the leads, such as 21, 22, 23, 24, individual to such equipments.

5 While there is shown herein a particular embodiment of the invention, it will be of course understood that the invention is not limited to the specific function or apparatus shown, but may be utilized in any circumstances where the selection of an idle circuit or set of circuits from a plurality of circuits or sets of circuits is desired by means of a simple, positive operating, automatic switch, and may be modified in 10 many ways while still retaining the characteristic features of the invention.

I claim:—

1. An automatic selecting switch, a plurality of circuits terminating in said switch, 20 test contacts for said circuits, a test circuit associated with said switch for testing the busy or idle condition of the circuits terminating in said switch as indicated on the test contacts individual to such circuits, and 25 contacts included in said test circuit controlled by said switch, such contacts being closed only during a definite portion of the movement of such switch from one of its positions in which connection is made to 30 one of said plurality of circuits to its next such position.

2. An automatic selecting switch, a plurality of circuits terminating in said switch, test contacts for said circuits, a test circuit 35 associated with said switch for testing the busy or idle condition of the circuits terminating in said switch as indicated on the test contacts individual to said circuits, and contacts included in said test circuit controlled by said switch and closed by said 40 switch in its movement from one position in which connection is made to one of said plurality of circuits to its next such position only after the contact of such test circuit 45 with the test contact of the circuit individual to the position from which such switch is moving has been opened, and maintained closed thereafter for a definite por-

tion of the movement of such switch into such next position. 50

3. An automatic selecting switch, a plurality of circuits terminating in said switch, test contacts for said circuits, a test circuit associated with said switch for testing the busy or idle condition of the circuits terminating in said switch as indicated on the test contacts individual to said circuits, a magnet for moving said switch from one of its positions in which connection is made to one of said plurality of circuits to its next 55 such position, a local circuit for said magnet closed by said switch as it moves from one position and opened by such switch as it comes into its next position, and contacts included in said test circuit controlled by 60 said switch and closed thereby only after such switch has opened contact with the circuit to which it is connected in the position from which it is moving, such contacts being opened by such switch when such local 65 circuit is opened on coming into its next position.

4. An automatic selecting switch, a plurality of circuits terminating in said switch, test contacts for said circuits, a test circuit 75 associated with said switch for testing the busy or idle condition of the circuits terminating in said switch as indicated on the test contacts individual to such circuits, contacts in such test circuit controlled by such 80 switch, such switch closing such contacts in said test circuit and controlling the closure of such test circuit to the respective test contacts in such relation that said test circuit is complete only for a definite period while 85 such switch is coming into position to make connection to one of such plurality of circuits.

In witness whereof, I hereunto subscribe my name this twentieth day of February, 90 A. D. 1914.

LIPA POLINKOWSKY.
